UNITED STATES PATENT OFFICE.

AUGUST LORENZ HELLERMANN, OF DUSSELDORF, GERMANY.

APPARATUS FOR MAKING CORRUGATED AND CREASED WOODEN SHAVINGS.

1,229,747.

Specification of Letters Patent. Patented June 12, 1917.

Application filed April 2, 1917. Serial No. 159,307.

To all whom it may concern:

Be it known that I, AUGUST LORENZ HELLERMANN, a citizen of the German Empire, and resident of Dusseldorf, Germany, have 5 invented certain new and useful Apparatus for Making Corrugated and Creased Wooden Shavings, of which the following is a specification.

My invention relates to an apparatus for 10 making corrugated and creased wooden shavings. With this object in view, I arrange in the throat of a tool, suitable for separating shavings from wood, *e. g.* a plane, a resistance which projects into the 15 path of the shavings as they pass the throat so as to obstruct their progress.

Such corrugated or creased shavings are 20 suitable as a stuffing for cushions, etc., a filling for filters, as a packing material, and also as a material for litter or the like.

To use ordinary, *i. e.* such shavings that 25 undergo no further treatment, as a stuffing or a packing material, is very old. These shavings, however, have the drawback that 30 they become unresilient when a considerable pressure is continually exerted on them. In order to keep the shavings resilient, which 35 is necessary if they are to be successfully used for any of the purposes specified, I arrange a resilient resistance in the path of the shavings separated from the wood which, in obstructing their progress, creases or corrugates them. Shortly after they have 40 been separated, the shavings are comparatively soft and yielding so that they do not break and remain in their corrugated or 45 creased condition after leaving the plane.

The apparatus for creasing or corrugating the shavings can be adapted to hand 50 tools as well as to planing machines. Owing to its simple construction and smallness, it can also be easily adapted to existing hand planes or existing planing or wood wool making machines. In a planing machine it 55 may, for instance, be arranged in the drawer for the dressing knives, in a wood wool making machine in the cutter slide.

Reference is to be had to the accompanying drawings in which I have illustrated 60 my invention by way of example, and in which—

Figure 1 is a lateral view of a plane provided with my apparatus, partly broken away; Fig. 2 is a plan view of said plane; 65 Figs. 3 and 4 are cross-sections of the plane on lines 3—3 and 4—4 of Fig. 1, respec-

tively; Fig. 5 is a detail elevation of the parts effecting the corrugation or creasing of the shavings; Fig. 6 is a section on line 60 6—6 of Fig. 5; Figs. 7 to 9 illustrate some stages of the corrugating or creasing process.

The plane, comprising a stock *a*, a cutter *b* and a cover iron *c*, is of the usual construction. In the passage or throat of the stock *a* is a parallel guide *d* which is fixed to a plate *e*. This plate is held on the stock by means of screws. A slide *f* is movable in said parallel guide and supported 70 by screws *g* which pass through slots *h* of guide *d*, see Figs. 4 and 5. Fixed to the upper end of slide *f* is a bracket *i* which passes through a further slot *k* of guide *d*, see Fig. 4, and carries a screw *l* to which 75 is attached one end of a spring *m*. The other end of said spring *m* is held by a bracket *n* fixed to plate *e*. At its lower end, slide *f* has two bearings *o*, in which a pin *p* is carried. A flap *r* is fixed on this pin by 80 means of lateral lugs *q*. An adjustable spring *s* tends to keep this flap in the position shown in full lines in Fig. 5.

I prefer to divide the shavings into a plurality of narrow strips, for which object I arrange a cutting device preceding the cutter of the plane and making a series of parallel cuts in the surface to be smoothed. In the construction illustrated, this cutting device is a roller *t* having a 85 plurality of circular edges. The pin on which said roller revolves is held in two plates *u* inserted in the sides of the stock *a* and held by screws *v*. The holes in plates *u* through which said screws pass are elongated so that the plates *u* may be displaced and the roller *t* raised or lowered accordingly. A set screw *w* is provided for each plate *u*.

A shaving *z*, after being divided into 100 strips by the cutting device (roller *t*) is raised by the cutter *b* as usually and travels upward on the cover iron *c* until it engages flap *r*, see Fig. 7. This flap forms an obstruction, causing the shaving to become 105 creased or corrugated. When the plane travels farther, the shaving first raises slide *f* against the action of spring *m* and then begins to turn flap *r*, as indicated in Fig. 8. The tension of springs *m* and *s* should be 110 so regulated that slide *f* is displaced first, and then flap *r* begins to yield. Finally, the shaving displaces the flap and the slide

to such an extent that it is able to pass under the flap, see Fig. 9. The resistance of slide *f* and flap *r* may be regulated as desired by adjusting springs *m* and *s*, respectively, according to the desired thickness of the shavings or the extent to which they are to be corrugated or creased. It will be observed that the slide *f* and the flap *r* are movable lengthwise of the throat or passage through which the shaving *z* is expelled; the pivot *p* is located at one side of said passage in such a position that a radius drawn from the center of the pivot to the point at which the flap *r* is first engaged by the end 15 of the shaving *z*, will be approximately perpendicular to the longitudinal axis of said passage, see Fig. 7. The movement of the slide *f*, while lengthwise of the throat through which the shaving *z* passes, is preferably not exactly in line with the axis of said throat, but oblique thereto, thus forming a better clearance between the cover iron *c* and the flap *r* when the slide *f* moves outward to the position shown in Fig. 9. 20

Obviously, it makes no difference whether the plane is moved over the wood, as is the rule in hand planes, or the wood is moved over the plane, as in planing machines.

The shavings so obtained may be disinfected, or impregnated with fire-proof materials, if desired.

I claim:

1. In an apparatus for making corrugated and creased wooden shavings, a passage or throat through which said shavings pass, a cutter for separating said shavings from the wood, and a resilient resistance arranged in the path of said shavings and movable lengthwise of said passage.
2. In an apparatus for making corrugated and creased wooden shavings, a passage or throat through which said shavings pass, a cutter for separating said shavings from the wood, and a resilient part movable lengthwise of said passage engaging that side of said cutter on which the shavings are moving.
3. In an apparatus for making corrugated and creased wooden shavings, a passage or throat through which said shavings pass, a cutter for separating said shavings from the wood, a cover iron on said cutter, and a resilient part movable lengthwise of said passage engaging that side of said cover iron on which the shavings are moving.
4. In an apparatus for making corrugated and creased wooden shavings, a passage or throat through which said shavings pass, a cutter for separating said shavings from the wood, and a resilient pivoted flap movable lengthwise of said passage engaging that side of said cutter on which the shavings are moving.
5. In an apparatus for making corrugated and creased wooden shavings, a passage or

throat through which said shavings pass, a cutter for separating said shavings from the wood, a cover iron on said cutter, and a resilient pivoted flap movable lengthwise of said passage engaging that side of said cover iron on which the shavings are moving.

6. In an apparatus for making corrugated and creased wooden shavings, a passage or throat through which said shavings pass, a cutter for separating said shavings from the wood, a slide adapted to move in a guide connected with said cutter, and a resilient part carried on said slide and engaging that side of said cutter on which the shavings are moving.

7. In an apparatus for making corrugated and creased wooden shavings, a passage or throat through which said shavings pass, a cutter for separating said shavings from the wood, a cover iron on said cutter, a slide adapted to move in a guide connected with said cutter, and a resilient part carried on said slide and engaging that side of said cutter on which the shavings are moving.

8. In an apparatus for making corrugated and creased wooden shavings, a passage or throat through which said shavings pass, a cutter for separating said shavings from the wood, a resilient slide adapted to move in a guide connected with said cutter, and a resilient part carried on said slide and engaging that side of said cutter on which the shavings are moving.

9. In an apparatus for making corrugated and creased wooden shavings, a passage or throat through which said shavings pass, a cutter for separating said shavings from the wood, a cover iron on said cutter, a resilient slide adapted to move in a guide connected with said cutter, and a resilient part carried on said slide and engaging that side of said cover iron on which the shavings are moving.

10. In an apparatus for making corrugated and creased wooden shavings, a passage or throat through which said shavings pass, a cutter for separating said shavings from the wood, a slide adapted to move in a guide connected with said cutter, a pull-back spring attached to said slide, and a resilient part engaging that side of said cutter on which the shavings are moving.

11. In an apparatus for making corrugated and creased wooden shavings, a passage or throat through which said shavings pass, a cutter for separating said shavings from the wood, a cover iron on said cutter, a slide adapted to move in a guide connected with said cutter, a pull-back spring attached to said slide, and a resilient part engaging that side of said cover iron on which the shavings are moving.

12. In an apparatus for making corrugated

- gated and creased wooden shavings, a passage or throat through which said shavings pass, a cutter for separating said shavings from the wood, a slide adapted to move in a guide connected with said cutter, a pull-back spring attached to said slide, a flap pivoted on said slide, and a spring engaging said flap and said slide and tending to force said flap against said cutter.
- 5 13. In an apparatus for making corrugated and creased wooden shavings, a passage or throat through which said shavings pass, a cutter, a cover iron on said cutter, a slide adapted to move in a guide connected with said cutter, a pull-back spring attached to said slide, a flap pivoted on said slide, and a spring engaging said flap and said slide and tending to force said flap against said cover iron.
- 10 14. An apparatus for making corrugated shavings, comprising a cutter for paring said shavings from the material, a passage
- 15 or throat, and a yielding resistance arranged in the path of said shavings and movable obliquely with reference to the longitudinal axis of said passage.
- 20 15. An apparatus for making corrugated shavings, provided with a cutter for paring shavings from the material, a passage or throat through which the shavings are expelled, and a yielding flap pivoted at one side of said passage and adapted to engage the free end of the shaving in said passage, the radius connecting the center of the pivot axis with the point of the flap initially engaged by the free end of the shaving, being approximately perpendicular to the longitudinal axis of said passage.

In testimony whereof I have signed this specification.

AUGUST LORENZ HELLERMANN.
